UNITED STATES PATENT OFFICE

FRANK P. MILLER, OF MEADVILLE, PENNSYLVANIA

INSERTED-BLADE CUTTER

Application filed May 16, 1925. Serial No. 30,786.

The invention forming the subject of this application aims to provide a rotary cutter of the inserted blade type in which the location and arrangement of the adjusting and thrust collar provides for the expeditious and simultaneous adjustment of the blades, and overcomes the need of reducing the diameter and consequently the strength of the intermediate portion of the carrier or 10 reamer body for the accommodation of the adjusting and thrust collar as is now necessary with the reamers and other cutters on the market.

Other objects and advantages will be apparent during the course of the following description.

In the accompanying drawing forming a part of this application and in which like numerals are employed to designate like 20 parts throughout the same.

Figure 1 is a fragmentary perspective of an inserted blade reamer embodying the invention;

Figure 2 is a detail sectional view through the forward portion of a reamer, the view illustrating the improved adjusting means for the blades;

Figure 3 is a front end elevation of the reamer, parts being broken away;

Figure 4 is a group view illustrating the internal adjusting collar and one of the blades.

In the drawing wherein for the purpose of illustration is shown a preferred embodiment of the invention, the numeral 5 designates a carrier for a plurality of blades 6. Figures 1 and 2 illustrate that the blades 6, which may be of any desired number, are received in gradually deepening grooves 7 and are securely held in an adjusted position by locking pins 8, the locking pins in turn being held in place by set screws 9. However, any suitable means may be employed to secure the blades in place without in any way departing from the spirit of this invention.

Figures 1, 2 and 3 illustrate that the forward end of the carrier or reamer body 5 is provided with an annular groove 10 for the reception of what might be said to be

an internal adjusting and thrust collar 12, the periphery of which is provided with coarse square or acme threads 14 which engage transverse ribs 16 on the inner edges of the blades.

As the collar 14 flatly contacts with the inner wall of the groove 10, turning of the collar in the proper direction will result in the forward movement of the blades to bring about an increase in the cutting diameter of the tool. Figures 1, 3 and 4 plainly illustrate that the collar 14 is provided in the front side thereof with oppositely located notches 18 for the reception of a suitable tool by means of which the collar may be turned. Or, if desired, lugs or other tool engaging means may be provided on the collar for use in adjustment.

It might be said that the invention forming the subject of this application includes the thrust collar 12 mounted on a central spindle or extension 22 on one end of the reamer body and provided with a threaded connection with the inner edges of the blades so that the turning of the collar on the spindle will result in expansion of the reamer or the like.

Particular attention is directed to the fact that the arrangement of the thrust collar at the forward end of the body and in engagement with the blades overcomes the need of reducing the diameter of the body adjacent the rear ends of the blades for the accommodation of the collar. Therefore, the reamer body retains its full diameter and strength and in these respects compares favorably with the solid or one piece reamer.

Having thus described the invention, what is claimed as new is:—

A rotary cutter comprising an elongated body having grooves, blades in said grooves and having their inner edges formed with transverse ribs, the forward portion of said body being provided with an annular groove, an adjusting and thrust member in the annular groove at the forward portion of the body and having contact with the inner wall of the groove to hold the adjusting and thrust member against endwise

movement in one direction with respect to the body, said adjusting and thrust member being confined to the forward end of the body and provided with peripheral threads engaged with the transverse ribs on the inner edges of said blades, whereby the turning of said member in one direction will advance said blades.

5 In testimony whereof I affix my signature.

10 FRANK P. MILLER.
